BOTTLE

Stanley N. Barbee, Los Angeles, Calif.

Application June 22, 1953, Serial No. 25,588

Term of patent 14 years

(Cl. D58—8)

To all whom it may concern:

Be it known that I, Stanley N. Barbee, a citizen of the United States, residing at Los Angeles, California, have invented a new, original, and ornamental Design for a Bottle, of which the following is a specification, reference being had to the accompanying drawing, forming a part thereof.

Fig. 1 is a front elevational view of a bottle, showing my new design.

Fig. 2 is a top plan view thereof.

Fig. 3 is a bottom plan view thereof.

The sides of the bottle, not shown are the same as the side shown.

I claim:

The ornamental design for a bottle, as shown and described.

STANLEY N. BARBEE.
